UNITED STATES PATENT OFFICE.

JOHN C. McLAUGHLIN, OF JERSEY CITY, NEW JERSEY, ASSIGNOR TO UNDERWOOD TYPE-WRITER COMPANY, OF NEW YORK, N. Y., A CORPORATION OF NEW JERSEY.

TYPE-WRITING MACHINE.

No. 889,144.

Specification of Letters Patent.

Patented May 26, 1908.

Application filed July 9, 1907. Serial No. 382,828.

To all whom it may concern:

Be it known that I, JOHN C. McLAUGHLIN, a citizen of the United States, residing in Jersey City, in the county of Hudson and State of New Jersey, have invented certain new and useful Improvements in Type-Writing Machines, of which the following is a specification.

This invention relates to card-holders for use on the cylindrical platen of a typewriter, and particularly to means for securing the holder.

The object of the invention is to improve and simplify the means for releasably securing the holder upon the platen. To this end I provide a hook or latch to catch under the hub of the platen, and a finger-piece therefor.

In the accompanying drawings, Figure 1 is a front elevation of a typewriter platen showing my improved device applied thereto. Fig. 2 is a view of the right-hand end of Fig. 1. Fig. 3 is a view of the left-hand end of Fig. 1 showing the latch released. Fig. 4 is a view similar to Fig. 3, but showing the latch locked. Fig. 5 is a perspective of the card-holder.

1 indicates the platen mounted upon a shaft 2 by means of hubs 3. The card-holder 30, 4 comprises a card-holding strip 4^a of springy sheet metal running along, and conforming to the curvature of, the platen, and having card-holding teeth 4^b; said strip having an arm 5 at each end and said arms extending 35 down over the heads of the platen, and forked, as at 6, to straddle the hubs 3 of the platen. The end of one of said arms is provided with claws 7 which catch over the head 8 of the platen to secure the holder. The 40 other arm is provided with a hook or latch 9 pivoted thereto above the forked portion, as at 10, and catching under the platen hub to lock the holder in place, said hook having finger-piece 11 at its upper end for swinging 45 it into and out of engagement with said hub.

To release the holder, the finger-piece is pressed forwardly, thereby swinging the hook rearwardly from the Fig. 4 to the Fig. 3 position, thereby releasing this end of the card-holder from the platen. Upon lifting said 50 end, the claws 7 slip off from the platen head 8. To replace the holder, the operation is reversed.

It will be seen that the entire latch, including the finger-piece, is below the top of 55 the platen, or within the cylindrical contour of the platen, so that any part of the latch will not interfere with the paper which is feeding around the platen.

Having thus described my invention, I 60 claim:

1. In a card-holder for use on the cylindrical platen of a typewriter, the combination with a card-holding strip of sheet metal running along the platen and having both 65 ends forked to straddle the hubs of the platen, of a hook pivoted to one end of the card-holder to catch under the platen-hub to lock the holder in place; the other end of said card-holder having claws to catch under the 70 platen head.

2. In a card-holder for use on the cylindrical platen of a typewriter, the combination with a card-holding strip of sheet metal running along said platen and having its ends 75 forked and bent to straddle the hub of the platen, of a hook pivoted to one of said ends above the forked portion and catching under the platen-hub to lock the holder in place, and a finger-piece for swinging the hook; the 80 other end having means to catch under the platen head.

3. In a card-holder for use on the cylindrical platen of a typewriter, the combination with a card-holding strip of sheet metal 85 running along said platen and having its ends forked and bent to straddle the hub of the platen, of a hook pivoted to one of said ends to catch under the platen hub to lock the holder in place, the other of said ends having 90 claws to catch under the head of the platen.

4. In a card-holder for use on the platen of a typewriter, the combination of a card-holding strip of metal having arms at its ends extending down over the platen-heads, and a 95 latch pivoted to one of said arms to catch under the hub of the platen, said latch having a finger-piece at its upper end; the latch and finger-piece being within the cylindrical contour of the platen, and the other of said arms 100 provided with means to catch upon the platen head.

JOHN C. McLAUGHLIN.
